ACTUATING TIMER WITH UNIFIED CONTROL

Original Filed Dec. 15, 1917 3 Sheets-Sheet 3

Inventor:

Raymond D. Smith

UNITED STATES PATENT OFFICE.

RAYMOND D. SMITH, OF PLEASANTVILLE, NEW YORK, ASSIGNOR, BY MESNE ASSIGNMENTS, TO TREMONT PRODUCTS CORPORATION, OF BOSTON, MASSACHUSETTS, A CORPORATION OF MASSACHUSETTS.

ACTUATING TIMER WITH UNIFIED CONTROL.

Original application filed December 15, 1917, Serial No. 207,303, Patent No. 1,493,771. Divided and this application filed May 12, 1924. Serial No. 712,739.

This invention relates in general to timing mechanism for governing automatic actuation of electric switches, gas valves, etc., and particularly concerns timer mechanism of the type wherein the timer may be energized and set in operation by the same control handle that operates the switch contacts, or gas valve.

The subject matter of this invention is 10 divisional from that of my issued United States Patent, No. 1,493,771.

By this invention I am enabled to employ, say, a switch preferably with spring actuated contacts of comparatively large electrical capacity, an associated timing mechanism, and a common control handle or other operating agency by means of which the switch may be directly operated by hand to control a circuit in the manner of an ordinary switch, and also operated automatically thru agency of the timing mechanism at a pre-determined time, whereas in the mechanism of my co-pending application, the switch and the timer were designed 25 to be operated by respectively different handles.

Other advantages will be clear from the 30 illustrative embodiment of my invention which is shown in the accompanying drawings wherein;

Fig. 1 is a front elevation of my improved timer mechanism as applied for the sake of illustration to a two-blade, knife or blade switch having spring operated contacts,— 35 the switch panel being shown as broken away to expose some of the timer parts.

Fig. 2 is a partial plan view showing some 40 of the detent parts for controlling the switch blades.

Fig. 3 shows my improved timer mechanism in front elevation, the switch parts being wholly omitted better to show the parts back of the panel.

Fig. 4 shows in right elevation, and 45 partially in central section, the complete switch and timer mechanism.

Fig. 5 is a vertical section through a part 50 of the timer operating mechanism taken on the vertical plane 5—5 in Fig. 4, looking in the direction of the arrows.

Fig. 6 is a plan view taken in section on the horizontal planes 6—6 in Fig. 4.

Fig. 7 is a sectional view similar to Fig. 5 but showing the parts differently positioned, together with more of the associated mechanism.

Fig. 8 is largely diagrammatic and shows a still different operative position of the parts in Fig. 5.

Fig. 9, also diagrammatic, indicates these 60 same parts in their normal position, or that position which they always tend to assume.

Fig. 10 is a sectional view on the plane 10—10 in Fig. 4.

In Figs. 1 and 4, binding posts for the 65 circuit lead wires 2 appear at 3. The conductive blades 4 of usual construction are friction-pivoted respectively in lower terminal hinge clips 5 mounted on a vertical support panel 6, of slate or other suitable 70 insulating material, so as to swing into and out of circuit-closing engagement with upper terminal clips 7. A brace bar 8 of insulating material bridges these blades at 75 their tops, but in place of the usual control handle for operating the blades, this brace bar carries a bracket mounting 9 for a detent catch finger 11 pivoted at 12 and urged by a spring 13 to a position as shown in Fig. 4, wherein a lower portion 14 of 80 said finger abuts against the brace bar 8, and an upper portion 15 extends upwardly to a position for interceptive engagement with a detent 16 carried between, and at the extremities of the double armed detent lever 85 18, which is pivoted at 19 to a bracket 20 mounted on the top edge of the support panel 6.

The common control handle 22 for switch and timer is fixedly carried by a separately 90 pivoted, actuating structure comprising a two-legged upright swinging arm 23 that in turn is carried rigidly by, and as part of, the horizontal straddle-bar 24, each end of the latter being pivoted at 25 to bracket 95 terminals 26 extending forwardly from either side of the panel base. The entire actuating structure above described will hereinafter be referred to as the actuator.

A powerful, coiled, spring 27 connects 100 an anchorage projection 28 of the actuator and a corresponding anchorage projection 29 of the blade structure, this spring normally acting to hold the actuator and the

blade structure together as shown in Fig. 4, where buffer lugs 30 formed as extensions of the bracket 9 are shown as seated in spring buffer clips 31 carried by the actuator 5 for shock-absorbing purpose.

It should be noted that the angle made by the forward engaging edge 32 of catch finger 11 relative to the path of travel of detent 16 as carried by detent lever 18 is such 10 as to exert pressure on this detent in a direction that will tend to displace said detent upwardly and out of the path of said finger to permit switch-opening movement of the blade structure whenever the detent lever 15 18 is free to yield. On the other hand, this angle is not such as to set up reactive pressure on the pivoted catch finger 11 in a direction to cause the latter to yield downwardly to permit such switch-opening movement of the blade structure; although it will 20 be evident from inspection of the mechanical relation of parts, as shown in Fig. 4, that movement of the blade structure to close the switch will always be permitted 25 freely by such downward yielding of the catch finger whenever the detent arm 18 is locked against upward yielding movement.

It is thus apparent that the blade structure is normally free to be moved to and 30 from its switch-closing position, and that to lock the same therein, it is necessary merely to prevent upward yielding movement of the detent lever 18. As one of the various possible ways to cause the timing mechanism 35 to effect automatic switch action when desired, I block, and at a predetermined time thereafter release, the detent lever 18 (respectively to prevent and to permit such yielding movement thereof) by means of a simple timer mechanism hereinafter to be 40 described.

When the detent arm 18 is blocked against yielding, swinging displacement of the actuator from its broken line position shown 45 in Fig. 4 will obviously separate the actuator from the blade structure and tension the connecting spring 30. To establish the parts thus tensioned, a locking strut arm 34 is friction-pivoted at 35 to the actuator 50 structure, said arm at its free end riding through an opening 36 in the panel 6 and being guided therein by a check pin 37 that horizontally spans said opening and passes through a longitudinal slot 38 in said strut arm. A notch 39 at the far end of this slot 55 is adapted to engage with the check pin to hold the actuator in its broken-line position in Fig. 4. The strut arm 34 may, however, at any time disengage from the check pin 37 60 by pressing downwardly with the thumb on a plunger trip rod 40 that passes centrally through the handle and at its lower end is bent to extend through, and to be guided in, an elongated slot 42 in the side of the actuator structure, thereby to engage with a

tripping extension 43 of the strut arm. A plunger spring 44 normally acts to hold the plunger rod 40 in its uppermost position.

The timer mechanism before referred to, is contained, for the most part, in a closed 70 chamber within a metallic mounting box 45 back of the panel 6. Pivoted at 46 to the rear face of the support panel 6 is a bell crank lever comprising a short arm 47 that extends horizontally to the left from said pivot, as shown in broken lines, Fig. 1, and terminates in a shelf-lug 48 directly beneath and engaging the lower end of a universal presser coupling 50, that at its upper end similarly engages with a rearward extension 80 51 of the detent lever 18 to receive presser impulses therefrom. The other, and longer, or feeler arm 52 of this bell crank lever is angular and extends obliquely downwardly terminating in a rearwardly turned end 53. 85 Mounted for rotation adjacent to this lower end of feeler arm 52, is a timer cam 55 normally so positioned rotatively that a notch 56 in the periphery thereof registers with said end 53 of the arm 52 to permit the 90 movement thereof radially inwardly of the cam, as would obviously be caused by the upward yielding of detent arm 18 heretofore mentioned. A light spring 57, however, acts yieldingly to hold the said end 95 of feeler arm 52 out of said notch and to retain lever 18 against stop 17 and the detent 16 in its lower position for engagement with catch finger 11. The tendency of finger 11 to displace detent 16 from its path, however, 100 is of such relative magnitude as to overcome the action of spring 57. Obviously, therefore, when the notch 56 in cam 55 registers with the end of feeler arm 52, yielding of the detent lever to release the blade structure for switch opening will be permitted 105 by entrance of arm 52 into this notch. But if this notch 56, as shown in full lines in Fig. 1, is displaced from such registering position, yielding of the detent lever 18 will 110 be positively blocked by engagement of feeler arm 52 with the periphery of the cam.

Cam 55 is fixedly mounted on the main and winding spindle 58 of a simple, self-contained escapement retarded time movement shown most fully in Fig. 4. Mounted for independent rotation on the same spindle is a large retarding gear 59 that is in mesh with a train of smaller retarding gears not designated by number because well 115 known in structure and function to those skilled in the art. Power for driving this retarding train and for simultaneously rotating cam 55 in one direction is had by storing tension in the band spring 60. This 120 spring at one end is connected to the winding spindle 58 and at the other end 62 to a frame stud 63. The spindle 58 has bearings in front and rear frame plates 64, 64 125 of the timing movement.

The total rotative movement of the main spindle 58 and of the cam 55, fixed thereon, is limited approximately to one complete turn. A graduated dial 70 is mounted on the front of the support panel 6. The band spring 60 always tends to rotate the cam 55 clockwise to a stop-limited position wherein the peripheral notch 56 in the cam 55 is positioned as also indicated in broken lines 10 to register with the end of feeler arm 52.

From the foregoing, it will be clear that when the timer parts are normally de-energized and positioned, the blade contact structure of the switch will promptly follow the actuator directly to open or close the switch in the usual manner. When, however, it is desired to cause the switch to perform an automatic action, as to break a circuit, say, for extinguishing the lights, 15 the actuator is swung to its locked position shown in full lines in Fig. 4 against the tension in spring 27,—corresponding movement of the blade structure being prevented by the cam-locked detent 16 in a manner 20 hereinafter described. Spring 27, upon timed return of notch 56 in cam 55 to its position for registering with the end feeler arm 52, will then cause a quick movement of the blade structure to open the switch. 25 As the impact between the blade structure and the actuator is considerable, the buffer lugs 30 and clips 31, or other suitable devices may be employed to absorb the shock.

I may provide as a means for winding and 30 setting in operation the timer movement, a system of gearing that may receive operating impulse from a gear segment, such as shown at 74. This gear segment is carried at the rear end of an arm 75 that is 35 formed to extend through a lateral opening 75 in the wall of the timer compartment, and is carried as a fixed part of the actuator straddle bar 24, thereby to swing in fixed relation to the actuator about the latter's 40 pivot.

In a rear corner of the timer compartment, I may conveniently mount, by means of 45 screw studs, 77, 77, an angle-plate rack 78 having teeth on each of its longitudinal 50 edges and constrained for vertical movement by a long slot 79 in one of its sides that engages with said screw studs.

This rack by one of its toothed edges is 55 positively enmeshed with segment 74 to slide up and down correspondingly to swinging movement of the actuator, and by another toothed edge engages an idler gear 80 rotating on a fixed stud 82 that is mounted in the rear wall of the timer box 45. This idler 60 gear is in turn enmeshed with a pinion 83 rotatably mounted on a similar fixed stud 84. The latter stud, however, is co-axial with the winding spindle 58 of the timer movement although structurally separate 65 therefrom.

As shown in Fig. 10, the pinion 83 is fixed to a common hub 87 with a winding disc 85 although between said pinion and disc, a timer gear 86 of greater diameter is also mounted freely to turn on, and relative to, 70 said hub for purposes later to be explained. The ratio of gearing is such that a full swinging stroke of actuator in its direction to open the switch rotates the winding disc 85 substantially one complete turn in a 75 counter-clockwise direction, Figs. 3, 5, 7, 8, and 9.

Also mounted on stud 84, and adjacent to hub 87, is an escapement disc 90 having a bearing hub 89 and that carries two forwardly projecting prongs 91, engaging at diametrically opposite points, with corresponding openings in a winding plate 95 that is fixedly carried on the main winding spindle 58, Figs. 4 and 6. The escapement 85 disc 90 is also freely rotatable on stud 84 and has connection with the winding disc 85 only through releasable engagement in one direction between a cam lug 93 carried on the winding disc 85 and a trippable latch 90 94 carried on the opposing face of the escapement disc 90. This latch is normally positioned by a light spring 96 against a stop pin 97 carried on the escapement disc as shown in Figs. 5 and 8 but may yield to the 95 opposite limit of its swing as determined by another pin 98 also carried on the escapement disc 90 as shown in Figs. 7 and 9. When in its normal position, the rearwardly 100 turned end 99 of the latch 94 is adapted to be engaged by an edge 100 of the cam lug 93, these parts, however, being capable of interference at no other points.

The timer setting gear 86, heretofore mentioned, carries on its forward face a trip 105 pin 102 extending into the path of a projecting portion 103 of the latch 94, which extends forwardly beyond the periphery of escapement disc 90. Two idler pinions 104 afford gearing connection of said timer setting gear 86 with a similar gear 105 fixedly carried on an arbor 106 that has a bearing 110 65 in the support panel 6, and carries directly in front of the latter the pointer-hand 66 with the usual handles 67, 67, and a co-operating time indication dial 70. This pointer-hand has no direct connection with the timer cam 55 nor the spindle 58 but is held established and stationary in such position as it may be desired to adjust the same, 115 by the detent plunger ball 107, adapted to seat in openings 108 circularly arranged in the gear 105. Obviously, the rotative position of the pointer-hand bears a constant relation to the rotative position of trip pin 102, 120 and by means of the handles 67, 67, such rotative position may be varied at will.

The operation is as follows:

The timer control parts are shown in their normal positions in Fig. 9. Here the 130

pointer-hand 66 is supposed to be positioned at "zero", and the actuator is in its broken line position indicated in Fig. 4. It will be seen that the trip pin 102 is holding outwardly the end 99 of latch 94 that normally is positioned to be engaged by the lug 93, and that the notch 56 in cam 55 registers with the end 53 of feeler arm 52, so that upon the switch-opening stroke of the actuator (and consequent rotation of the winding disc 85 in a counter-clockwise direction, (Fig. 9) no engagement will occur between said lug 93 and latch 94. The timer cam 55 and timer movement will remain, therefore, undisturbed permitting the detent roller 16 to yield upwardly and permit passage of catch finger 11, and movement of the blade structure to open the switch, in the usual manner.

Assuming now, that before such switch-opening stroke of the actuator, the pointer-hand 66 is displaced from its zero position, and the trip pin 102 thereby revolved counter-clockwise to some position such as shown in Fig. 8, then latch 94 will be urged by spring 96 into the path of lug 93, so that when the latter is moved with the winding disc 85 by said stroke of the actuator, the escapement disc 90 will be picked up and rotated in a direction to wind the band spring 60 of the timing movement. Such winding rotation of the escapement disc is, of course, accompanied by corresponding rotation of the main spindle 58 and timer cam 55, and continues during the said stroke of the actuator until projection portion 103 of latch 94 is encountered by the trip pin 102. At this point the said latch will be disengaged from said lug and released for automatic timed return under the stored-up power in band spring 60, in the usual manner,—the lug 93 continuing through its full revolution corresponding to a full stroke of the actuator after being thus relieved of the escapement plate at the point predetermined by the setting of the trip pin 102.

Turning of escapement disc 90 to wind the movement spring 60 will not actuate the retarding train because a ratchet wheel 71, that is friction mounted against a shoulder on the spindle 58 through the axially exerted tension in spring 61, will slip under the retarding pawl 72 carried on the side of the large retarding gear 59 in the well known manner. The band spring 60 obviously will be wound to an extent proportional to the rotative displacement of escapement disc 90 and will play itself out as it drives the time train and restores escapement disc 90, and cam 55 to their stopped positions. Slow movement of cam 55 results from the retarding action of the gear train as transmitted to the spindle 58 through the friction hold thereon of ratchet wheel 71 consuming an interval of time proportional to the degree

of displacement of escapement disc 90 from its stopped position.

There are several features of operation that should be noted. Although lug 93 will always pick up and carry the escapement disc 90 counter-clockwise to a point predetermined by the setting of trip pin 102, yet operative interference of said lug, with latch 94, when passing in the opposite direction, is always prevented by the cam formation given to the lug 93 which causes natural yielding of latch 94, as shown in Fig. 5. Another point to be noted is that in order for the blade structure to be held in switch-closing position and tensioned for timed release, the timer cam 55 must be moved to displace the notch 56 therein from registering position with the end of feeler arm 52, before the blade structure encounters the detent roller 16. To provide for this, suitable operative lost motion, or clearance, is arranged between the blade structure and the detent 16 when the blade structure is fully seated in the terminal clips 7. But in addition to this back-lash, introduced for the purpose just described, a purely idle lost motion of greater extent is desirable to insure that even though the blade structure is not pushed entirely back to its switch-closed seat, the cam lug 93 will always return rotatively to an extent sufficient to pass into engaging relation with the latch 94,—ready, as shown in Fig. 9, on subsequent switch opening stroke of the actuator, to wind up and set in operation the timing movement, in the manner before explained. To make allowance for this additional and purely idle back-lash, peripheral elongation of the notch 56 in cam 55 is provided. It will be appreciated that the need of such idle lost motion is largely due to the fact that a small angular movement of the actuator results in a much greater angular movement of the timer cam. A positive stop for the spring-driven timer movement is provided by a pin 110 that engages a spur 112 on the winding plate 95, Figs. 3 and 4, it being clear from the arrangement as shown in Figs. 8 and 9, that at any time desired, direct return of these parts to their stopped, or normal, position to effect release of the blade structure or for other purpose, may be caused by turning the pointer-hand 66 in a clockwise direction back to "zero", which action will cause the trip pin 102 to impel the escapement disc 120 through engagement with latch 94, until these parts are returned to their positions as in Fig. 9, regardless of what position the cam lug 93 may at the time occupy.

It will be appreciated that whereas, for simplicity, I have chosen to disclose my improved timer arrangement as applied to an electric knife switch, the scope of the invention is by no means limited to such application. Thus I may as readily combine my 130

improved and simplified timer arrangement, with switch structures of radically different types, such as either rotary or push-button snap switches of standard and approved design; or my invention wherein all actuating control is concentrated in common main control handle, is as readily embodiable in timer mechanism for a gas-valve or other device, as for electric switches. As there is nothing generically different in a mechanical sense between the movements of an electric contact to make and break an electric circuit and the movements of the port control member of, for instance, a valve to open and close a conduit, it will clearly be understood that both are intended to be included by specific mention of either in any of the appended claims. Also I do not confine my invention to the manner of timer control whereby the timer holds back the switch contacts and later releases them for follow-up movement relative to the actuating handle. I could as well arrange the timer movement to operate the switch contacts by means of direct timer caused actuation of the switch actuator or in other ways if desired.

Therefore my invention will be understood as not confined to the specific embodiments thereof herein disclosed, but what I claim as new is:

1. In an electric time switch, the combination with a movable circuit-governing member; of resilient means for establishing tension tending to shift said member automatically between operative positions thereof; a separately mounted detent movable to and from a position for intercepting said member to prevent tension-caused shifting thereof; normally idle timing mechanism operatively related to said detent to control member-governing movements thereof; and a separate operating handle arranged by one movement to shift said member directly from one to another of its said operative positions independently of said timing mechanism and by another movement to subject said member to the operative tension of said resilient means; together with means for operatively connecting said actuator and said timing mechanism so that the former also energizes and sets in operation said timing mechanism.

2. In an electric switch, the combination with a movable contact member; of resilient means for establishing tension tending to cause circuit-breaking movement of said member; an actuator adapted to operate said member and further arranged on designed movement to energize said resilient means; a movable detent operatively related to said member for governing the said circuit-breaking movement thereof; and normally idle timing mechanism connected to be energized and set in operation by the said actuator movement that energizes said

resilient means, and adapted when so set in operation to control member-governing movement of said detent; together with an adjustable trip device, arranged to predetermine the operative setting of said timer mechanism and extent of the energization thereof as caused by said movement of said actuator.

3. Mechanism for timing operative movement of a detent-controlled device embodying, in combination; a detent-governing timer element mounted to be spring-impelled to a definite stop-limited position, with means automatically active to retard said element when the latter is manually displaced from its said position and released for spring-impelled return thereto; an operating handle mounted for limited swinging travel and adapted by said travel to tension said device for operative movement; means for coupling said operating handle with said element so that the latter is displaced from its said position by said swinging travel of the former; and an adjustable trip device operatively related to said coupling means and arranged automatically to free said element from said handle at a selectable predetermined point in said travel of the latter.

4. An electric switch response timer embodying, in combination with a movable switch contact member; a relatively movable switch actuator arranged by one movement to establish said member in circuit-making position; means adapted automatically to displace said member from its said position to break the circuit; and a normally inactive timer mechanism including a locking element for preventing said displacement of the contact member; and a retarded spring motor adapted to drive said element to a position for operatively releasing said member; together with connections whereby movement of said switch actuator additional to said circuit making movement sets in operation said spring motor automatically to actuate said element and effect the release of the contact member after a predetermined time.

5. An electric switch response timer embodying, in combination with a movable switch contact member; a relatively movable switch actuator arranged by one movement to establish said member in circuit-making position; means adapted automatically to cause displacement of said member from its said position to break the circuit; and a normally inactive timer mechanism including a locking element for preventing said displacement of the contact member, and a retarded spring motor adapted to drive said element to a position for operatively releasing said member; together with connections whereby another movement of said switch actuator winds and sets in operation said spring motor automatically to actuate

said element and effect the release of the contact member after a predetermined time.

6. Electric switch control mechanism, embodying in combination with an oscillatory contact member; an oscillatory actuator mounted to swing with and positively to impel said member in one direction of its oscillation and further arranged for swinging displacement relative to said member in the opposite direction of oscillation; a spring connecting said actuator and said member so that said displacement of the former relative to the latter tensions the latter for circuit-switching follow-up movement; a detent movable to a position to intercept said member thereby to prevent its said follow-up movement; means to hold said actuator when tension is established in said connecting spring; and normally idle timing mechanism including a retarded spring motor having operative connections with said actuator whereby member tensioning displacement of the latter winds and sets in operation said motor, with a movable timer element for holding said detent in its intercepting position;—said element being connected to said motor thereby to be impelled to a stop-limited position wherein said detent is released to free said member.

7. A time limit switch embodying in combination, a circuit controlling contact, a handle movable a designed distance to throw said contact to close the circuit, a power spring tensionable by said handle to throw said contact to open the circuit, a spring impelled timer mechanism, connections whereby a portion of the movement of said handle conditions said timer mechanism to delay the circuit opening throw of said contact, and means to vary and predetermine the portion of said handle movement which acts upon said timer thereby to predetermine the duration of said delay.

45 8. A time limit switch embodying in combination, a circuit controlling contact, a handle movable a designed distance to throw said contact to close the circuit, a power spring tensionable by said handle to throw said contact to open the circuit, a timer, operatively related to said contact means operated by a portion of the movement of said handle to condition said timer for a period of operation thereby to delay during said period the opening throw of said contact, and means to vary and predetermine the portion of said handle movement which acts upon said timer, thereby to predetermine the said period of timer operation.

60 9. An electric switch operating response governor embodying in combination with a circuit-controlling member of the switch; a relatively movable actuator therefor arranged by one movement to establish said member in a maintained operative position

thereof; means adapted to be energized for automatically shifting said member from its said position; and a normally inactive slow-acting timer adapted to render said means operative to shift said member a substantial interval of time after said timer is set in operation; together with connections between said actuator and said timer whereby movement of said actuator sets in operation said timer.

75 10. In switch timing mechanism, in combination, a current switching contact reciprocating between open and closed positions, a spring to tension said contact for quick circuit switching action, a timer conditionable to effect said spring caused action of said contact, and a handle connected to operate said contact, and to tension said spring, and to be movable without movement of said contact for conditioning said timer.

80 11. In switch timing mechanism, in combination, a current switching contact reciprocating between open and closed position, a power spring to tension said contact for quick current switching action, a timer normally stationed in limit position, a motor spring for impelling said timer to said position to effect actuation of said contact by said contact spring, and a handle connected to establish said contact selectively in open 90 or closed position without establishment of opposing bias in said power spring, and connections whereby said handle displaces said timer from said limit position and energizes said motor spring.

95 12. In switch timing mechanism, in combination, a timer, a motor spring to impel said timer, a switch contact governable by said timer, a power spring to actuate said contact, a handle connected to tension both 105 said motor spring and said power spring, said handle further being connected to effect current switching movement of said contact after tensioning said motor spring and without varying the tension already established in said motor spring.

13. In a flow control timing mechanism, in combination, a timer, a motor spring to impel said timer, a flow control governable by said timer, a power spring to actuate 115 said flow control, a common handle connected to tension both said motor spring and said power spring, said handle being movable to operate said flow control subsequent to tensioning said motor spring and without further varying the tension in said motor spring.

120 14. In combination with a switch and timing mechanism, a handle to throw said switch directly without intermediate action of said timing mechanism and connections whereby said handle is also operative to condition said timing mechanism to cause an automatic actuation of said switch.

125 15. In switch timing mechanism, in com- 130

- bination, a spring impelled timer, a spring actuated reciprocating contact governable by said timer, a common handle connected to tension said timer spring and also to tension 5 said contact spring, said handle being further connected to throw said contact in both directions without interference by said timer after tensioning said timer spring and without varying the tension in said timer spring.
- 10 16. In switch timing mechanism, in combination with a reciprocating switch contact, means to tension said contact for quick circuit switching action, a spring driven timer to govern said contact action, a handle having 15 connections to throw said contact in both directions without interference by said timer and to energize said contact tensioning means by movement relative to said contact and further having connections to energize and 20 set in operation said timer.
17. In combination with power means for actuating a device to be timed, a timer normally stationed at limit position and displaceable from said position for self returning travel to effect the actuation of said device through said means, a common handle for operating both said power means and for said timer, and connections whereby movement of said handle in one direction both 25 displaces said timer from limit position and energizes the power means to actuate said device.
18. Timing mechanism embodying, in combination with the device to be timed, a spring driven time movement, a timer controlling the actuation of said device and impellable by said movement to a limit position, a handle operable in one direction to displace said timer from said position and simultaneously wind the movement spring, and means permitting reverse movement of both said handle and said timer without unwinding said spring.
- 30 19. In combination, timing mechanism, a device to be timed, a time setting handle, a time movement spring arranged to be energized by displacement of said handle from one position, said handle being manually returnable to said position without unwinding said movement spring.
- 35 20. In combination, timing mechanism, a device to be timed, a time setting handle connected to operate selectively with and without time control the device to be timed, a time movement spring arranged to be energized by displacement of said handle from one position when operating said device with time control, said handle being manually returnable toward its said position without unwinding said movement spring.
- 40 21. A time limit switch embodying in combination, a circuit controlling contact, a handle movable a full distance to throw said contact to close the circuit, a power spring tensionable by said handle to throw said contact to open the circuit, a spring impelled timer, mechanism whereby a portion of the movement of said handle conditions said timer to delay the circuit opening throw of said contact, and means to vary and predetermine the conditioning of said timer as effected by the movement of said handle through its said full distance.
- 45 22. Time control mechanism embodying in combination, a flow control, a handle to operate said flow control, a timer to control the operation of said flow control and also operated by said handle, and setting means to vary and predetermine the action of said handle upon said timer.
- 50 23. In combination with an electric switch, a handle actuatable for opening and closing said switch, a timer mechanism effective during its running period to delay an action of said switch consequent to actuation of said handle, connections whereby said handle starts the running period of said timer mechanism, and means separate from said handle to vary and predetermine the duration of said running period prior to the starting thereof by said handle.
- 55 24. In combination with an electric switch, a handle actuatable for opening and closing said switch, a timer mechanism effective during its running period to delay an action of said switch consequent to actuation of said handle, connections whereby said handle starts the running period of said timer mechanism, and means separate from said handle and adjustable both prior to and subsequent to the actuation of said handle which starts said running period thereby to vary and determine the duration of said period.
- 60 25. Time control mechanism embodying in combination, a flow control, a handle connected to operate said flow control in definite mechanical relation thereto, and a timer for controlling automatic operation of said flow control and connected to be operated by said handle in variable mechanical relation to said flow control.
- 65 26. In combination with a flow control, timing mechanism, a handle to operate said control directly without intermediate action of said timing mechanism, and connections whereby said handle conditions said timing mechanism to cause an automatic actuation of said control.
- 70 27. A time limit flow control embodying in combination, a flow controlling member, a handle movable to throw said member to affect the flow, a power spring to throw said member back to its original position, a time giving mechanism, connections whereby movement of said handle conditions said time giving mechanism to govern the said throw-back of said member, and means settable separately from movement of said handle with connections to vary and predetermine thereby the time at which said time giving member is thrown.

ing mechanism shall cause the said throw-back of said member, said means remaining so set and so operating on subsequent actuations of said member and conditioning of said mechanism by said handle, thereby to repeat the same time determining function without further manipulation of said means.

28. In a time limit switch, the combination with a movable contact member, of resilient means for causing circuit breaking movement of said member, a common handle to operate said member and to energize said resilient means, normally idle timing mechanism connected to be set in operation by movement of said handle, and adapted to control the action of said resilient means upon said member, together with an adjustable trip device settable separately from said handle and operative thereafter to repeatedly determine the period of running of said timing mechanism prior to its circuit breaking effect upon said member each time the timing mechanism is set in operation for that purpose by said handle.

29. In switch timing mechanism, in combination, a current switching contact, a power spring for effecting quick current switching action of said contact, a normally

idle time giving mechanism, and conditionable to run for governing said spring caused 30 action of said contact, and a handle connected to set said contact selectively both in open and closed positions, and connections whereby movement of said handle conditions said time giving mechanism for running, 35 together with a trip settable separately from said handle, and means rendering said trip operable to determine the period of running of said mechanism and the time of action of contact governed thereby.

30. In combination with a flow control and timing mechanism, a handle having a degree of movement to operate said control directly without intermediate effect of said timing mechanism, connections whereby said handle is also operative to condition said timing mechanism to cause an automatic actuation of said control, and a trip member stationable in variable positions to determine the time of said automatic actuation and to 50 vary same disproportionately to said degree of movement of said handle.

Signed at Boston, Massachusetts, this 8th day of May, 1924.

RAYMOND D. SMITH.
